UNITED STATES PATENT OFFICE.

CHARLES P. WATSON, OF PITTSBURG, PENNSYLVANIA.

PROJECTILE.

1,004,510.

Specification of Letters Patent. Patented Sept. 26, 1911.

Application filed January 13, 1910. Serial No. 537,901.

To all whom it may concern:

Be it known that I, CHARLES P. WATSON, a citizen of the United States, residing at Pittsburgh, in the county of Allegheny and State of Pennsylvania, have invented new and useful Improvements in Projectiles, of which the following is a specification.

My invention relates to bullets or projectiles, and more especially to those employed in small arms, and has for its object to produce a soft metal bullet with a jacket of novel construction; to produce a mushrooming or expanding bullet of novel construction; and to provide a bullet or projectile with a packing ring or gas check of novel construction at its rear end.

The several improvements constituting my invention may all be embodied in one and the same bullet or projectile, and this 20 is the preferred construction, although they are capable of separate, as well as joint, use.

I am aware that projectiles for small arms have been provided with smooth, hard-metal jackets, and with wound jackets 25 formed of fibrous coated wire laid in exterior circumferential grooves formed in the metal of the body of the projectile. There are certain well recognized objections to a bullet or projectile for small arms provided 30 with a smooth hard-metal jacket. The wire and fabric wound bullets are also open to serious objection, especially when attempt has been made to use them with smokeless or other powder producing very high velocities, owing to the fact that the wrappings would not remain in place, but would be detached from the body of the bullet by centrifugal force due to its high velocity.

The objections to both forms of cased bullets referred to are overcome by my invention which I will now proceed to describe, reference being had to the accompanying drawings, in which—

Figure 1 is an elevation of a bullet embodying my improvements, part of the body at the nose of the bullet being broken away. Fig. 2 is a central longitudinal section of the bullet shown in Fig. 1. Fig. 3 is a transverse section thereof. Fig. 4 is an elevation 50 of a bullet different from that shown in Fig. 1, embodying some of the features of my invention, part of the nose of the bullet being broken away. Fig. 5 is a longitudinal sectional view of a bullet different from that 55 shown in any of the other views, embodying features of the invention. Fig. 6 is a detail

view of the coil of wire adapted to constitute a jacket for a bullet. Fig. 7 is a rear end view. Fig. 8 is a longitudinal section of the forward end of a projectile provided 60 with a nose piece of different form from those illustrated in the other views.

The body A of the bullet or projectile is formed of lead, or a compound including lead, and is of any usual or preferred shape. The bullet shown in Fig. 1 is provided with a separate nose piece B of harder metal than the body A, but of less specific gravity, with a hard-metal jacket C formed of coiled wire exteriorly surrounding the body, and a 70 packing ring or gas check D at the rear end of the bullet. The jacket is formed of a close coil of hard-metal wire, German silver for instance, the ends c of which are carried within the coil and left free and exposed. This jacket is incorporated into the bullet when the body A thereof is cast, that is to say, a coil like that represented in Fig. 6 is introduced into the bullet mold before the metal of the body is poured therein. 75 The result is that the metal flows into the grooves between the convolutions of the wire, and embeds the ends c thereof so that so intimate a union between the jacket and the body A is secured that it is impossible 80 to separate one from the other without destroying the integrity of the bullet. A jacket such as described will carry the lubricant required for a bullet or projectile of this nature, and prevents the metal of the 85 body from contact with the gun barrel and takes well to the rifling.

In casting the bullet shown in Fig. 1 the rear end of the body is formed with a shoulder d which provides a seat for an annular 95 split ring D which constitutes a packing or gas check. The ring D is applied to its seat after the bullet has been formed and preferably while the bullet is in the shaping and sizing die, at which time the rear end of the bullet is sufficiently expanded against the ring to securely hold it in place, or it may be cast on.

The features of the invention thus far described are applicable to a soft or hard 105 nose bullet. I have, however, shown it as applied to bullets embodying another feature of my invention which consists of a separate nose piece of metal harder than the body A but of less specific gravity. I 110 prefer to use aluminum or an alloy for such nose piece. The use of the hard nose piece

B causes an expanding or mushrooming of the bullet when it strikes. The nose piece being of much less specific gravity than the rest of the bullet has correspondingly less inertia and hence its motion is more quickly retarded upon striking an object than is the rest of the bullet, with the result that the body is instantly and violently expanded. The shape of the hard nose piece may be 5 changed to suit different conditions. For instance in Figs. 4 and 5 a spherical form of nose piece designated B' is shown.

In Fig. 1 is shown a form of nose piece designated B, so shaped as to constitute the 10 entire nose of the bullet. It is provided with a shoulder b back of which extends an ovoid portion or neck of reduced size b' that is embedded in the body of the projectile. That portion of the nose piece that is 15 embedded within the body A is corrugated grooved or roughened so as to secure a close and intimate engagement between these two parts, while the exposed part of the nose piece is preferably smooth. The form of 20 nose piece shown in Fig. 1 is especially advantageous if used in bullets that have to be forced into place within the gun barrel especially of an automatic arm and which, 25 when made entirely of soft metal, are liable to have their forward or nose ends deformed from this or other causes, which may 30 clog the arm and destroy accuracy of projectile when fired.

It is evident that a jacketed bullet such as 35 I have described can be made by any one

having a bullet mold, thus enabling a user of firearms to easily make his own jacketed projectiles, which is sometimes a matter of great convenience and importance. I believe that I am the first to have produced 40 a jacketed soft metal bullet that can be thus easily and successfully made without the necessity of expensive and complicated apparatus.

What I claim is:—

1. A projectile having a metal body and a metal jacket harder than the body and formed of a close coil of wire surrounding the body and intimately united thereto by the casting thereof. 45

2. A projectile consisting of a metal body and a hard metal jacket formed of a close coil of wire, the ends of the latter being embedded within the body. 50

3. A projectile consisting of a metal body and a jacket fitting about the body and formed of closely coiled wire, the ends of which are carried within the convolutions of the wire and left free, the metal of the body being cast about such ends of the wire. 55

4. A bullet or projectile formed of soft metal having a shouldered seat at its rear end, and a hard-metal split ring upon the said seat, the metal of the body being expanded to hold the ring upon its seat, substantially as set forth. 60

CHARLES P. WATSON.
